UNITED STATES PATENT OFFICE.

ALFRED R. SPOERL, OF BROOKLYN, AND WILLIAM L. GEISLER, OF HEMPSTEAD, NEW YORK.

TOUCH AND TECHNIC STOP FOR PIANOS.

SPECIFICATION forming part of Letters Patent No. 593,133, dated November 2, 1897.

Application filed November 16, 1896. Serial No. 612,265. (No model.)

To all whom it may concern:

Be it known that we, ALFRED R. SPOERL, of Brooklyn, in the county of Kings, and WILLIAM L. GEISLER, of Hempstead, in the 5 county of Queens, State of New York, have invented a new and Improved Touch and Technic Stop for Pianos, of which the following is a full, clear, and exact description.

The invention relates to mute attachments 10 for ordinary pianos; and its object is to provide a new and improved touch and technic stop for pianos and arranged to enable a performer to render the piano mute and to permit finger exercise with any degree of resistance to the keys.

The invention consists in a novel construction of the mute attachment; further, in a novel construction of the resistance for the keys, and, lastly, in a novel connection of 20 the mute attachment with the resistance, all as hereinafter described and claimed.

Reference is to be had to the accompanying drawings, forming a part of this specification, in which similar characters of reference indicate corresponding parts in all the figures.

Figure 1 is a cross-section of the improvement, showing the hammers locked out of action. Fig. 2 is a similar view of the same, showing the resistance out of action and the 30 hammers released. Fig. 3 is an enlarged sectional plan view of the improvement on the line 3 3 of Fig. 1. Fig. 4 is a cross-section of the same on the line 4 4 of Fig. 3. Fig. 5 is a like view of part of the same, showing the resistance out of engagement with the keys. Fig. 6 is an enlarged sectional side elevation of the resistance on the line 6 6 of Fig. 7. Fig. 7 is a sectional front elevation of the same on the line 7 7 of Fig. 6. Fig. 8 is a side elevation 35 of the same with parts in a different position and parts broken out. Fig. 9 is a sectional side elevation of the same on the line 9 9 of Fig. 7, and Fig. 10 is a similar view of the same on the line 10 10 of Fig. 3.

The upright piano shown in the drawings is provided with the usual casing A and keys B, connected at their rear ends by links C with jack-levers C', carrying a jacket C², engaging the hammers D for throwing the latter upon the strings E to sound the same in

the usual manner. The hammers D normally rest on a hammer-rail D', and the jack-levers C' rest at their forward ends on a rail F, preferably made in the form of a threaded roller, journaled in suitable bearings in arms 55 F', pivoted at F² to a rail of the action, as is plainly shown in Figs. 1, 2, and 4.

The arms F' rest on vertically-disposed rods or posts F³, fitted to slide in suitable bearings in the casing or frame A, and each 60 of the said rods F³ carries a forwardly-extending foot F⁴, resting at its free end on an arm F⁵, secured to a laterally-extending shaft G, mounted to turn in suitable bearings formed in a bracket A', attached to the casing A.

The shaft G extends a suitable distance above the rear ends of the keys B, and one end of the shaft G is provided with a downwardly-extending arm G', connected by a link 70 G² with a lever G³, fulcrumed on the keyboard-frame and provided with a handle G⁴, under the control of the operator, to permit the latter to swing the lever G³ transversely and turn the shaft G to cause the feet F⁴ to 75 be raised or lowered by the action of the arms F⁵. When the feet F⁴ are raised, on throwing the lever G³ forward in the direction of the arrow a', (see Fig. 4,) then the rods F³ are lifted and the arms F', carrying the rail 80 F, are moved upward to swing the jack-levers C' upwardly, thereby lifting the links C out of engagement with the rear ends of the keys B and causing the jacks C² to swing the hammers D into an intermediate position, as indicated in Fig. 1. When the several parts are in this position, the keys B when pressed do not act on the links C, and consequently the hammers are not actuated and the piano 85 is rendered mute.

When the lever G³ is moved in the inverse direction of the arrow a', then the feet F⁴ move downward as the arms F⁵ swing in a downward direction, and consequently the rods F³, arms F', and rail F move downward 95 to permit the jack-levers C' to swing in a like direction and allow the hammers D to fall back to their normal resting position on the rail D', as illustrated in Fig. 2. The links C now rest again on the rear ends of the keys 100

B, and when the latter are played the hammers are actuated and the strings are sounded in the usual manner.

When the lever G³ is moved forward into the position shown in Figs. 1 and 4 and the piano is rendered mute, as described, then a resistance II is thrown in engagement with the keys B, and when the lever G³ is moved in the inverse direction of the arrow a' then the said resistance II is thrown out of engagement with the keys at the time the hammers D move into an active position, as described above and shown in Fig. 2.

The resistance II is actuated from the shaft G, and the latter is provided for this purpose with gear-wheels G⁵ in mesh with segments I', formed on the frame I, carrying the resistance II. The frame I is mounted to turn loosely on a longitudinally-extending shaft J, journaled in the brackets A', previously mentioned. The frame I is formed with guide-plates I² and I³, one above the other, and carrying rods K, adapted to rest on the top of the keys B between their pivots and the rear ends, as is plainly indicated in the drawings, it being understood that each key is adapted to be engaged by a corresponding rod K. The downward movement of each rod K is limited by projections or pins K', adapted to be seated on the upper guide-plate I², as is plainly shown in Fig. 7.

The top of each rod K is engaged by a spring L, extending transversely and secured at one end to a rail I⁴, forming part of the frame I. On the free end of each spring L is secured a block L', normally resting on a plate N, supported in the frame I, the block being also adapted to engage with its top a second plate N', held vertically adjustable in guideways I⁶, forming part of the frame I. Suitable screws N² engage the plate N' to raise or lower the same and permit the spring L to swing more or less, according to the resistance desired to be given to the corresponding key B. It is understood that when a key is pressed at the time the resistance II is in an active position then the upward swinging of the rear end of the key lifts the corresponding rod K, and the latter moves in contact with the spring L to swing the same upward until the block L' strikes against the under side of the plate N' to limit the further swinging of the spring L in this upward direction. More or less tension can be given to the spring L by means of a laterally-extending bar O, extending over the springs L and secured at its ends to arms O', secured by screws O² to plates P, fitted to slide transversely in suitable guideways I⁷, formed in the sides of the frame I. (See Figs. 6, 7, and 9.)

Each of the plates P is formed at its under side with a rack P' in mesh with a gear-wheel P², secured on the shaft J, and on one outer end of this shaft J is secured a gear-wheel Q in mesh with a rack Q', fitted to slide transversely in suitable bearings formed on the frame A. The rack Q' is formed with a for-

wardly-extending arm Q², pivotally connected with a lever Q³, fulcrumed on the keyboard-frame and formed with a handle Q⁴, 70 adapted to be taken hold of by the operator. The lever Q³ is provided with a pointer R, adapted to indicate on a graduation R', held on the keyboard-frame at one side of the last treble-key, as plainly indicated in Fig. 3. 75

Thus it will be seen that when the operator swings the handle Q⁴ of the lever rearwardly then the gear-wheel is turned by the rack Q' in the direction of the arrow b', (see Fig. 6,) whereby the shaft J is turned in the same direction and the gear-wheels P² are rotated to shift the racks P', and consequently the plates P, backward to move the bar O over the springs L toward their free ends and increase the tension of the said springs to give some 85 resistance to the rods K when the latter are moved upward upon pressing the corresponding key B. The bar O can be adjusted up or down by moving its arms O' correspondingly upon loosening the set-screws O², so that the 90 said bar O does not engage the springs L until some time after the rods K have started on their upward movement upon pressing the keys B.

Now it will be seen that by the arrangement described any desired resistance can be given to the rods K to regulate the touch of the operator pressing the keys. Furthermore, the sliding motion of the said rods can be limited, if desired, by adjusting the plate N' 100 correspondingly in the guideways I⁶.

The rail I⁴ is preferably made vertically adjustable on the sides of the frame I, as indicated in Fig. 10, so as to adjust the springs L relative to the upper ends of the rods K, 105 and the springs L are adjusted vertically relative to the rods K by set-screws L², screwing into the bottom of the rail I⁴ against strips L³, of leather, felt, or like material, and engaging the under side of the springs between 110 their fastened ends and the rods K, as plainly shown in Figs. 4 and 6. The strips L³ render the springs noiseless.

When the lever G³ is in the position shown in Figs. 3 and 4, then the hammers D are in 115 an inactive position and the resistance II is thrown into an active position owing to the turning of the shaft G, as previously described, the said shaft by its gear-wheels G⁵ imparting a swinging motion to the frame I, 120 since the said gear-wheels engage the segments I'. When the lever G³ is shifted rearwardly to permit the hammers to fall back into their former resting position, then a 125 swinging motion is given to the frame I to cause the latter to assume the position shown in Figs. 2 and 5, whereby the rods K are moved out of engagement with the keys B, and the latter when pressed do not touch the 130 said rods, but actuate the hammers in the usual manner. The resistance II is now out of action and the hammers are in action, and when the lever G³ is in the position shown in Fig. 4 then the hammers are thrown out of

action and the resistance is thrown into an active position. (Shown in Fig. 4.)

Having thus fully described our invention, we claim as new and desire to secure by Letters Patent—

1. A device of the class described, provided with a resistance comprising rods fitted to slide, and adapted to rest on the keys, and springs pressing on the said rods, substantially as shown and described.

2. A device of the class described, provided with a resistance comprising rods fitted to slide, and adapted to rest on the keys, springs pressing on the said rods, and means, substantially as described, for increasing or decreasing the tension of the said springs, as set forth.

3. A device of the class described, provided with a resistance comprising rods fitted to slide and adapted to rest on the keys, springs pressing on the said rods, and means, substantially as described, for limiting the swinging motion of the said springs, as set forth.

4. A device of the class described, provided with a resistance comprising rods fitted to slide and adapted to rest on the keys, and springs pressing on the said rods, each of the said springs being provided at its free end with a block or weight adapted to swing between two plates, one of which is adjustable, substantially as shown and described.

5. A device of the class described, provided with a resistance, comprising a frame mounted to swing, and under the control of the operator, rods fitted to slide in the said frame and adapted to rest on the keys, and springs held on the said frame and engaging the said rods, each of the springs being provided with a block or weight at its free end, substantially as shown and described.

6. A device of the class described, provided with a resistance, comprising a frame mounted

to swing, and under the control of the operator, rods fitted to slide in the said frame and adapted to rest on the keys, springs held on the said frame and engaging the said rods, each of the springs being provided with a block or weight at its free end, and a bar adjustably held over the said springs for regulating the tension of the springs, substantially as shown and described.

7. A device of the class described, provided with a resistance, comprising a frame mounted to swing, and under the control of the operator, rods fitted to slide in the said frame and adapted to rest on the keys, springs held on the said frame and engaging the said rods, each of the springs being provided with a block or weight at its free end, a bar adjustably held over said springs for regulating the tension of the springs, and means, substantially as described, for adjusting said bar over the said springs, as set forth.

8. A device of the class described, provided with a resistance comprising a frame, rods fitted to slide in the said frame, springs pressing on the said rods, a bar adjustably held over the said springs, means for shifting the said bar, and a device for indicating the position of the bar relatively to the springs, as set forth.

9. A device of the class described, provided with a rock-shaft under the control of the operator and carrying arms, posts fitted to slide vertically and provided with feet engaging the said arms, hinged arms connected with the said posts, and a rail carried by the said hinged arms and adapted to engage jack-levers, substantially as shown and described.
